UNITED STATES PATENT OFFICE

DAVID TURCOTT, OF BELOIT, WISCONSIN, ASSIGNOR TO YATES-AMERICAN MACHINE COMPANY, OF BELOIT, WISCONSIN, A CORPORATION OF DELAWARE

AUTOMATIC TURNING MACHINE

Application filed November 4, 1929. Serial No. 404,596.

This invention has to do with automatic wood-turning lathes of the type in which the work is brought into engagement with rotating knives and is rotated on its own axis while in such engagement.

The primary object of the invention is to provide a novel work-handling device for use with such a lathe, which device acts before the cutting operation to center the work with respect to the chucks of the head and tail stocks and acts after the cutting operation to unload the work from the chucks.

While the foregoing statement is indicative in a general way of the nature of the invention, other objects and advantages will be evident to those skilled in the art upon a full understanding of the construction, arrangement and operation of the new centering and unloading device.

One form of the invention is presented herein for the purpose of exemplification, but it will of course be understood that the invention is capable of being embodied in other structurally different forms coming equally within the scope of the appended claims.

In the accompanying drawings:

Fig. 1 is a perspective view of a lathe equipped with the centering and unloading device of the invention;

Fig. 2 is a vertical transverse section through the lathe, showing the device in the act of positioning the uncut work in centered relation to the chucks;

Fig. 3 is a similar section, showing the carriage of the lathe advanced to cutting position and the device withdrawn from engagement with the work;

Fig. 4 is a similar section, showing the device in the act of unloading the finished work from the chucks; and

Fig. 5 is a section through one of the two duplicate units of the device, taken on the line 5—5 of Fig. 2.

The lathe shown in the drawings includes a main frame 10, a set of rotating knives 11 supported by the frame, a carriage 12 pivoted at 13 to the frame for movement toward and away from the latter, a head stock 14 on the carriage having a rotating chuck 15, a tail

stock 16 on the carriage having a rotating chuck 17, and a hand lever 18 pivoted at 19 to the frame and connected by a link 20 to the carriage for moving the latter to bring the uncut piece of rotating work gripped between the chucks 15 and 17 into engagement with the rotating knives 11.

The device which forms the subject matter of the present invention is in the nature of a lathe attachment and consists of two spaced spiders 21 and 22 which are duplicates of each other and act in unison upon the opposite ends of each piece of work placed in the lathe. A description of the spider 22 and its associated operating parts will therefore be sufficient, it being understood that such description applies as well to the spider 21.

The spider 22 is rotatably mounted at its center on a bracket 23 which is adjustably attached to the top of the carriage 12 by bolts 24. The spider is provided about its periphery with four L-shaped work-engaging arms 25, 26, 27 and 28 which serve in the order of their numbering to center with respect to the chucks 15 and 17 the pieces of work successively operated upon by the lathe.

When the carriage 12 is swung away from the frame 10 to receive an uncut piece of work between the chucks, the arm 25 assumes the position shown in Fig. 2, in which position it is temporarily held against accidental displacement by a spring-pressed indexing ball 29 in the hub of the spider, see Fig. 5, which ball seats in a cone-shaped recess 30 in a stationary disk 31 attached to the bracket 23. Similar recesses 32, 33 and 34 are provided in the disk 31 for accurately positioning the other arms when the latter subsequently assume the centering position in which the arm 25 is shown in Fig. 2.

The spider is provided at one side with four laterally projecting cam rollers 35, 36, 37 and 38 which coact with the opposite edges 39 and 40 of a blade-shaped cam 41 and also coact with one end of an inwardly spring-pressed finger 42 which is pivoted at 43 to the cam 41. The cam 41 is adjustably fastened to a forwardly extending bench-like portion 44 of the frame 10, and is provided at the lower extremity of the edge 40 with an ad-

justably positioned screw 45 with which the rollers also coact.

The device operates as follows:

Starting with the carriage 12 of the lathe 5 swung away from the frame 10 into loading position, as shown in Fig. 2, an uncut piece of work 46 is placed in the angles of the arms 25 of the spiders, which arms are so adjusted on the spiders as to accurately center the 10 work with respect to the chucks 15 and 17. After the chucks have been caused to grip the ends of the work firmly, the carriage is swung toward the frame.

As soon as the carriage starts to advance 15 toward the frame, the rollers 35 ride onto and over the edges 40 of the cams 41, thereby rotating the spiders part of one revolution in a counterclockwise direction to swing the arms 25 downwardly away from the work 20 into the position shown in Fig. 3. The cutting operation then takes place upon the work.

After the cutting operation has been completed, the carriage is swung away from the 25 frame again. As soon as the carriage commences its return movement, the outer ends of the fingers 42, being pressed into the paths of the rollers 38, engage with the latter and rotate the spiders a part of one revolution in 30 a clockwise direction into the position shown in Fig. 4, thereby bringing the rollers 35 into opposition with the edges 39 of the cams 41, whereupon the rollers 35 engage with the edges 39 and rotate the spiders still farther 35 in a clockwise direction into the position wherein the rollers 36 engage with the ends 40 of the screws 45 and bring the spiders to rest with the next arms 26 in correct position to center the next piece of work. During the 45 above described clockwise rotation of the spiders, the arms 25 lift the then finished piece of work 46 from between the chucks, which are retracted at that time, and raise the work into a position wherein it will slide forwardly off of the arms into a suitable receptacle.

The next piece of uncut work is then placed 50 upon the arms 26, which arms have now assumed the centering position previously occupied by the arms 25, and the above described operation of the centering and unloading device is repeated, the device assuming a position at the completion of each turning operation with the next arms on the spiders in readiness to receive and center the next piece of uncut work.

In the particular embodiment of the invention presented herein for the purpose of exemplification, the chuck 17 of the tail stock 60 is pneumatically operated in accordance with the invention disclosed and claimed in my co-pending application Serial No. 404,595, filed November 4, 1929, and is caused to be automatically retracted from the work by the 65 movement of the carriage away from the

knives just before the work is engaged and lifted from between the chucks by the unloading arms.

I claim:

1. In a lathe, a pair of chucks between 70 which the work is held during the cutting operation, a pair of arms for supporting the work in centered relation to the chucks before the work is engaged by the chucks, means for automatically lowering the arms from the work prior to the cutting operation, and means for automatically raising the arms beyond their centering positions after the cutting operation to remove the work from between the chucks. 75

2. In a lathe, a frame, a plurality of knives mounted for rotary movement on the frame, a carriage hinged for movement toward and away from the frame, head and tail stocks on the carriage having axially aligned chucks for holding a piece of work therebetween, a pair of rotatably mounted spiders on the carriage having spaced arms for supporting the work in alignment with the chucks, and coacting means on the frame and carriage for automatically moving the arms away from the work prior to the cutting operation and moving the work out from between the chucks upon completion of the cutting operation. 80

3. In a lathe, a pair of chucks between 85 which the work is held during the cutting operation, a pair of arms for supporting the work in centered relation to the chucks before the work is engaged by the chucks, means for automatically withdrawing the arms from the work prior to the cutting operation, and means for automatically returning the arms and carrying them beyond the line of the chuck axes after the cutting operation to remove the work from between the chucks. 90

4. In a lathe, a pair of chucks between 95 which the work is held during the cutting operation, means for supporting the work in centered relation to the chucks before the work is engaged by the chucks, means for automatically withdrawing said supporting means from the work prior to the cutting operation, and means for automatically returning said supporting means to the work and carrying it beyond the line of the chuck axes 100 after the cutting operation to remove the work from between the chucks. 105

5. In a lathe, a frame, a plurality of knives mounted for rotary movement on the frame, a carriage hinged for movement toward and away from the frame, head and tail stocks on the carriage having axially aligned chucks for holding a piece of work therebetween, a pair of rotatably mounted spiders on the carriage having spaced arms for supporting the work in alignment with the chucks, and coacting means on the frame and carriage for automatically moving the arms away from the work prior to the cutting operation and automatically moving the arms back to the 110

- work to remove the latter from between the chucks upon completion of the cutting operation.
6. In a lathe, a frame, a cutter mounted for rotary movement on the frame, a carriage hinged for movement toward and away from the frame, head and tail stocks on the carriage having axially aligned chucks for holding a piece of work therebetween, a pair of rotatably mounted spiders on the carriage having circumferentially spaced arms provided with L-shaped seats for supporting the work in alignment with the chucks, and means for turning the spiders first in one direction and then in the other, whereby to withdraw the seats from the work prior to the cutting operation and return the seats to the work to eject the latter from between the chucks after the cutting operation.
- 10 7. In a lathe, a frame, a rotary cutter mounted on the frame, a carriage, a pair of rotary chucks mounted on the carriage, means for moving the carriage toward or away from the frame to advance or retract the chucks with respect to the cutter, means for supporting a piece of work in centered relation to the chucks before the latter are advanced, means for withdrawing said supporting means from the work when the chucks are advanced, and means for returning said supporting means to the work to discharge the latter when the chucks are retracted.
- 15 8. In a lathe, a frame, a rotary cutter mounted on the frame, a carriage, a pair of rotary chucks mounted on the carriage, means for moving the carriage toward or away from the frame to advance or retract the chucks with respect to the cutter, means for supporting a piece of work in centered relation to the chucks before the latter are advanced, means for withdrawing said supporting means from the work when the chucks are advanced, and means for returning said supporting means to the work to discharge the latter when the chucks are retracted.
- 20 9. In a lathe, a frame, a rotary cutter mounted on the frame, a carriage, a pair of rotary chucks mounted on the carriage, means for moving the carriage toward or away from the frame to advance or retract the chucks with respect to the cutter, means for supporting a piece of work in centered relation to the chucks before the latter are advanced, means for withdrawing said supporting means from the work when the chucks are advanced, and means for returning said supporting means to the work to discharge the latter when the chucks are retracted.
- 25 10. In a lathe, a frame, a rotary cutter mounted on the frame, a carriage, a pair of rotary chucks mounted on the carriage, means for moving the carriage toward or away from the frame to advance or retract the chucks with respect to the cutter, means for supporting a piece of work in centered relation to the chucks before the latter are advanced, means for withdrawing said supporting means from the work when the chucks are advanced, and means for returning said supporting means to the work to discharge the latter when the chucks are retracted.
- 30 11. In a lathe, a frame, a rotary cutter mounted on the frame, a carriage, a pair of rotary chucks mounted on the carriage, means for moving the carriage toward or away from the frame to advance or retract the chucks with respect to the cutter, means for supporting a piece of work in centered relation to the chucks before the latter are advanced, and means for causing said supporting means to discharge the work from between the chucks after the latter have been retracted.
- 35 12. In a lathe, a frame, a rotary cutter mounted on the frame, a carriage, a pair of rotary chucks mounted on the carriage, means for moving the carriage toward or away from the frame to advance or retract the chucks with respect to the cutter, means for supporting a piece of work in centered relation to the chucks before the latter are advanced, and means for causing said supporting means to discharge the work from between the chucks after the latter have been retracted, said supporting means being so positioned when removing the work as to allow the latter to slide off the same.
- 40 13. In a lathe, a frame, a plurality of knives mounted for rotary movement on the frame, a carriage hinged for movement toward and away from the frame, head and tail stocks on the carriage having axially aligned chucks for holding a piece of work therebetween, a pair of rotatably mounted spiders on the carriage having spaced arms for supporting the work in alignment with the chucks, and coacting means on the frame and carriage for automatically turning the spiders first in one direction and then in the other, whereby to withdraw the arms from the work prior to the cutting operation and return the arms to the work to eject the latter from between the chucks after the cutting operation, said spiders turning in the last mentioned direction far enough to bring another pair of the supporting arms into centering position with respect to the chucks in readiness to center the next piece of work.
- 45 14. In witness whereof I have hereunto subscribed my name.

DAVID TURCOTT. 130

rotary chucks mounted on the carriage, means for moving the carriage toward or away from the frame to advance or retract the chucks with respect to the cutter, means for supporting a piece of work in centered relation to the chucks before the latter are advanced, means for withdrawing said supporting means from the work when the chucks are advanced, and means for returning said supporting means to the work to discharge the latter when the chucks are retracted, said withdrawing and returning means being automatically actuated by the movement of the carriage toward and away from the frame.
